HOSIERY AND METHOD OF KNITTING SAME

John H. Mueller, North Caldwell, N. J.

Application September 26, 1946, Serial No. 699,462

3 Claims. (Cl. 66—185)

1

This invention relates to knitted hosiery, and especially to hosiery produced initially as a flat fabric for the fashioning of stockings and other forms of hose.

The invention has reference, more particularly, to the knitting of the foot part of hose, whereby to widen an area thereof rearwardly of the toe portion and intermediate said toe portion and the narrowed arch or instep portion, so as to provide a widened interior to accommodate the normally wider span of the wearer's foot in the region of the big toe joint or a bunion with which the foot of the wearer may be afflicted, and thus to reduce restriction and accompanying irritating effect by the hose foot part upon such sensitive part of the wearer's foot, and consequently thereby assuring greater ease and comfort to the wearer.

The invention has for an object to provide a novel knitted hose foot structure wherein the knitted fabric, after being narrowed in the usual manner immediately forward of the heel part for snug fit beneath the arch of the wearer's foot, is widened out in the area or zone adjacently rearward of the toe portion narrowing, whereby to increase the width of the foot part in such area or zone for comfortable accommodation of the normally wider span of the wearer's foot in the region of the big toe joint, and especially if a bunion, with which the foot of the wearer may be afflicted, is present, while nevertheless maintaining a snug fit at the arch of the wearer's foot; and the invention has for a further object to provide a novel method of knitting, whereby such widened area or zone may be practically and easily obtained.

Other objects of this invention, not at this time more particularly enumerated, will be understood from the following description of the same.

An illustrative embodiment of the invention is shown in the accompanying drawings, in which—

Fig. 1 is a side view of the foot portion of a stocking constructed according to this invention so as to provide the same with a widened big toe joint or bunion accommodating area or zone; Fig. 2 is a diagrammatic view of the toe portion of the stocking blank and adjacent big toe joint or bunion accommodating area or zone illustrative of one method of knitting the fabric thereof to produce the latter area or zone; and Fig. 3 is an enlarged fragmentary yarn loop diagram, corresponding to the area A in Fig. 2, and showing the formation of some widening courses whereby the increased big toe joint or bunion accommodating area or zone is obtained.

Similar characters of reference are employed in the above described views, to indicate corresponding parts.

2

In the production of a blank for a stocking embodying the present invention, the knitting thereof is carried out in the well-known manner by knitting machinery familiar to the art, whereby to form the welt, leg and heel portions, including the narrowing 10 of the foot part beyond the heel portion 11 and at the arch portion 12 of said foot part. The knitting of the blank is thereafter continued until the area of the foot part desired to be widened for big toe joint or bunion accommodation is reached, which area is to be located adjacently rearward of the later formed and narrowed toe portion 13, and is generally indicated by the reference character 14 in Fig. 1.

To produce the big toe joint or bunion accommodating widened area 14 of the foot part, the widening operation is performed by the round heel attachment of a knitting machine, and is accomplished by manipulating loops of selected courses in a manner similar to the manipulation thereof in effecting narrowing of the fabric, except that instead of moving the transferred loops inwardly relative to the selvages, the transferred loops are moved outwardly or toward the selvages, so as to extend the latter and thus widen the fabric therebetween. In order, therefore, to distinguish the latter method of loop manipulation, which might, except for the contradiction of terms, be called "narrowing out," I shall hereinafter designate the manipulation as "widening," indicated by reference character W in Fig. 1, in contradistinction to normal narrowing manipulations.

35 Illustrative of one method of knitting, and the resultant widened area or zone produced thereby in the foot part of the hose, after the heel portion 11 and arch narrowing 10 has been knitted, a desired number of normal courses 15 are knit until the area of the foot part is reached which is desired to be widened, whereupon a series of widening sections of selected number and spacing is produced. To produce said widening sections, a selected number of loops of a normally knit course, which extend inwardly from the respective selavage edges of the blank, are picked up by a first dip of a loop transfer means of the knitting machine, whereby to be removed from the machine needles, then shifted outwardly one needle toward the selavage edges, and then redeposited upon the needles, thus forming a first widening course 16 (see Fig. 3). The next succeeding course is thereupon knit so that wales thereof are in line with the transferred and outwardly shifted loops of said widening course 16, whereupon the same number of loops of said succeeding course, which extend inwardly from the selavage edges of the fabric, are picked up by a second dip of said loop transfer means, 60 whereby to be likewise removed from the ma-

chine needles, then shifted outwardly one needle toward the selvage edges, and then redeposited upon the needles, thus forming a second widening course 17 (see Fig. 3). These operations complete one widening section, whereby the fabric of the blank is widened out to the extent of two needles on each side thereof toward the respective selvage edges of the blank. After such widening section 16-17 is produced, the knitting is continued to produce a selected number of normal courses 18, whereupon another widening section, comprising successive widening courses 16 and 17, is knit. These operations are continued until a widened area or zone of desired dimensions and longitudinal extent is obtained, whereafter the knitting of the foot part of the hose is completed by knitting the narrowed toe portion 13 in any desired selected manner well known to the art.

As above indicated, the starting of the widening courses 16 and 17 may be begun any selected number of loops or needles inwardly from the respective selvage edges of the fabric, accordingly as it may be desired to position the openings 19 and 20, respectively left in the body of the fabric at the inner ends of said respective widening courses 16 and 17, in given spaced relation to the seam of the finished hose. If, e. g., as shown, these openings 19 and 20 are desired to be exposed in the finished fabric, then the widening courses 16 and 17 are started a considerable number of needles inwardly from the respective selvage edges of the fabric, but if, on the other hand, it is desired that said openings be concealed in the seam of the finished hose, then said widening courses should be started not more than two or three needles inwardly from said selvage edges of the fabric, so that, when said selvage edges are joined to produce the seam of the finished hose, said openings will be enclosed within and covered by the seam formation.

As illustratively shown in the drawings, widening courses 16 and 17 are each started within the fabric respectively twenty needles inwardly from the respective selvage edges of the blank. It will be understood however that such start may be optionally made any lesser or greater number of needles, accordingly as it may be desired to space the resultant openings 19 and 20 from the finished hose seam. Since each successive widening course 16 and 17 is shifted outwardly one needle, each widening section formed thereby widens the fabric of the blank at each side thereof to the extent of two needles, or a total of four needles. The number of widening sections, with intervening normal courses, may also be subject to variation, but by knitting eight such widening sections 16-17 as shown (see Fig. 2), spaced by a suitable number of intervening normal courses 18, a total widening of eight times four needles, or thirty two needles, is produced, whereby to add substantial width to the fabric in the widened area, in amount dependent somewhat upon the gauge employed.

The distortion of the wales, due to the formation of the widening courses 16 and 17, is not unduly noticeable in the finished fabric, since, by reason of the elasticity of the knitted fabric, the finished product tends to resume normal wale appearance, and also the selvage edges tend to substantially straighten out.

While it is preferable to provide the widening

sections as comprised of the double or successive widening courses 16 and 17, as above described, since in knitting machines the selvage forming means cooperates with two needles, said widening sections may, if desired, each comprise a single widening course, with intervening normal courses of desired number, provided the selvage forming means is modified accordingly.

From the above, it will be obvious that the present invention provides a novel foot structure for hose, and novel method of knitting the same, by which the foot part of the hose is substantially widened in an area or zone adapted to be coincident to the wider span or breadth of the wearer's foot when the hose is worn, and which widened area or zone is especially well adapted to accommodate the hose foot part to the foot of a wearer possessed of a bunion, whereby undue restriction and uncomfortable binding of the foot part over and upon the bunion is substantially eliminated, with consequent greater ease and comfort to the wearer.

Having now described my invention, I claim:

1. In a foot part of a knitted fabric blank for producing hose, a widened area adjacently rearward of the narrowed toe portion thereof comprising a plurality of successive widening sections spaced by normal courses, each widening section comprising two successive widening courses, each widening course having a selected number of loops thereof, which extend inwardly from the respective selvage edges of the blank, shifted one needle outward toward said selvage edges.
2. In the foot part of a knitted fabric blank for producing hose including the usual heel, arch narrowing and toe narrowing formations, a widened area intermediate said arch and toe narrowing adjacently rearward of the latter comprising a plurality of successive widening sections, normal courses alternated with said widening sections, and each widening section comprising two successive widening courses, each widening course having a selected number of loops thereof, which extend inwardly from the respective selvage edges of the blank, shifted one needle outward toward said selvage edges, whereby the fabric is widened by extension of each selvage edge by two needles at the outer end of each widening section.
3. The method of knitting the foot part of a hosiery blank to provide a widened area beyond the usual arch narrowing and adjacently rearward of the toe narrowing which comprises transferring a selected number of loops at each end of successive normally knit courses outwardly one needle each toward and so as to extend the selvage edges of the blank at which said courses terminate, thus forming a widening section, thereafter knitting a selected number of normal courses, and then repeating production of said alternate widening and normal courses until a widened area of desired dimensions and longitudinal extent is obtained.
